UNITED STATES PATENT OFFICE.

ALFRED STELZNER, OF WIESBADEN, GERMANY.

PRESERVE-JAR.

SPECIFICATION forming part of Letters Patent No. 447,479, dated March 3, 1891.

Application filed October 29, 1890. Serial No. 369,696. (No model.)

To all whom it may concern:

Be it known that I, ALFRED STELZNER, a subject of the Emperor of Germany, residing at Wiesbaden, in Germany, have invented certain new and useful Improvements in Preserve-Jars, of which the following is a specification.

This invention relates to a preserve-jar so constructed as to effectively exclude the air from the contents of the jar.

The invention consists in the various features of improvement more fully pointed out in the claims.

In the accompanying drawings, Figure 1 is a vertical central section of my improved preserve-jar. Fig. 2 is an elevation of the same, and Fig. 3 an enlarged section through the joint.

The letter A represents a preserve-jar of suitable form and material. This jar has formed on the inner face of its neck an upwardly-extending flange r' , and behind the same an annular groove r . The flange r' is lower than the neck, so that when an inner cover d is placed upon the flange it will be substantially flush with the upper edge of the neck, as shown in Fig. 3. Around the bottle there is formed a laterally-opening groove h , adapted for the reception of a rubber gasket k . d' is an outer cover, adapted to fit over the inner cover d , and having a tapering downwardly-depending flange d^2 , that embraces the bottle-neck. This flange has a corrugated inner surface adapted to compress the gasket k .

In use the jar is filled and some of the juice is poured into the groove r . The lid d is then put in place and is covered by a piece g of pig's bladder or similar material. This

piece of bladder is of sufficient length to extend over groove h . The gasket k , being next slipped into the groove, will hold the bladder in place. Finally the lid d' is forced down to compress the gasket and form a tight joint.

The jar when sealed, as described, is placed into a bath of boiling water.

To remove the lid d' but moderate force is necessary. Between the two lids d d' a small space should be left to permit a proper adjustment of the outer lid.

If desired, the flange d^2 may be provided with a shoulder d^3 , and a similar shoulder a may be formed around the jar A. Around the shoulders d^3 a a string a' is passed which is knotted and has sealed ends. Thus the jar cannot be opened without breaking the seal.

What I claim is—

1. The combination of a jar having an inner flange r' and an outer groove h with an inner cover d , an outer cover d' , having tapering flange d^2 , and with a gasket k , adapted to be received by groove h , substantially as specified.

2. The combination of a jar having an inner flange r' and groove r and an outer groove h with a gasket k , an inner cover d , and an outer cover d' , having an internally-corrugated flange d^2 , adapted to compress the gasket, substantially as specified.

In testimony whereof I hereunto sign my name, in the presence of two subscribing witnesses, this 9th day of October, 1890.

ALFRED STELZNER.

Witnesses:

ALVESTO S. HOGUE,
JEAN GRUND.
